UNITED STATES PATENT OFFICE

2,560,404

HICCUP TREATING APPARATUS

Thomas D. Assmar, Jewett City, Conn.

Application January 31, 1949, Serial No. 73,733

6 Claims. (128-33)

1

This invention relates to new and useful improvements and structural refinements in therapeutic machines, and the principal object of the invention is to facilitate treatment of chronic hiccough conditions.

This object is achieved by the provision of the instant apparatus, intended primarily for use in hospitals and similar institutions, wherein the patient is seated upon a reciprocatively vibratile platform with his hands grasping a vibratile hand bar, while his arms are restrained against vibration by relatively stationary arm straps.

The invention also contemplates the provision of what may be referred to as a mask for the face of the patient, these various arrangements cooperating in producing mild muscular and neurotic reflexes or shock which, in turn, are believed to counteract spasmodic contractions of the diaphragm to which the cause of hiccoughs is generally attributed.

An important feature of the invention lies in its simplicity of construction, ease of manipulation, and in its adaptability to repeated use in a series of treatments of any one particular patient, without causing any apparent discomfort.

With the above more important objects and features in view and such other objects and features as may become apparent as this specification proceeds, the invention consists essentially in the arrangement and construction of parts as illustrated in the accompanying drawings, in which:

Figure 1 is a perspective view of the invention, showing a patient in situ therein, illustrated in phantom lines;

Figure 2 is a cross sectional view, taken substantially in the plane of the line 2-2 of Figure 1;

Figure 3 is a perspective view of a fulcrum joint used in the invention;

Figure 4 is a cross sectional view, taken substantially in the plane of line 4-4 in Figure 1;

Figure 5 is a fragmentary plan view, taken substantially in the plane of the line 5-5 in Figure 1; and

Figure 6 is a cross sectional view, taken substantially in the plane of line 6-6 in Figure 1.

Like characters of reference are employed to designate like parts in the specification and throughout the several views.

Referring now to the accompanying drawings in detail, the invention consists of a hiccough treating apparatus designated generally 55

2

by the reference character 10, the same embodying in its construction a substantially rectangular framework or base 12 provided with a plurality of support blocks 14 on which is reciprocably positioned a vibratile platform 16.

A pair of spaced parallel angles 18 are secured to the under surface of the platform 16 and being engageable with the blocks 14, the angles 18 constitute what may be referred to as guides, which permit the platform 16 to reciprocate in the direction of the arrows 20 (see Fig. 1).

A bracket 22 projects laterally from the framework or base 12 and carries an upright support 24, the upper end of which, in turn, is provided with a further bracket 26, notched as at 28.

A fulcrum joint 30, best shown in the accompanying Figure 3, is pivotally mounted in the notch 28 of the bracket 26 by means of a fulcrum pin 32, this pin extending through an aperture 34 formed in a flat mid-portion 36 of the joint 30, as will be clearly apparent. It is to be noted that the joint 30 also includes a pair of internally screw-threaded sockets 38, whereby the joint is effectively employed for rigidly connecting together upper and lower portions 40, 42, respectively, of what may be referred to as a lever.

It is to be noted that by virtue of this structural arrangement, the lever is fulcrumed intermediately of its length, the upper portion 40 thereof being provided with a T-coupling 44 carrying a hand bar 46, while the lower portion 42 of the latter is equipped with a fork 48 provided with opposed slots 50 to accommodate a pivot pin 52 whereby the fork 48 is connected to a bracket 54 rigidly secured to the aforementioned platform 16.

Accordingly, when the platform 16 reciprocates in the direction of the arrows 20, an oscillatory or reciprocating movement will be imparted to the hand bar 46 by the lever 40, 42, and it should be particularly noted that inasmuch as the lever has the fulcrum thereof disposed intermediately of its length, the platform 16 and the hand bar 46 will be reciprocated in relatively opposite directions.

The reciprocation of the platform 16 is effected by means of an electric motor 56 mounted upon the framework 12 and operatively connected through the medium of a gear box 58 to a counter-shaft 60 which, in turn, is connected by a flexible coupling 62 to a crankshaft 64 rotatably journaled in suitable bearings 66. These bearings are mounted on suitable brackets 68 carried by the framework 12, as will be clearly apparent.

The crankshaft 64 carries a pitman arm 70 which is operatively connected by a pivot pin 72 to a U-shaped bracket 74 secured to the platform 16. Accordingly, upon actuation of the motor 56, rotation of the crankshaft 64 will impart a reciprocating, vibratile movement to the platform as indicated by the arrow 20, while at the same time the hand bar 46 is vibrated in the direction of the arrow 16, as has been already explained.

If desired, the hand bar 46 may be provided at one end thereof with a hand grip 78, while its remaining end is equipped with a cup holder 80, the purpose of which will be hereinafter explained.

A tubular, upright standard 82 is secured at the lower end thereof to the framework 12, and one arm of an L-shaped extension 84 is slidably telescoped in the standard 82, being adjustable vertically as to height by means of suitable wing screws 88 with which the standard 82 is provided. The remaining arm of the extension 84 extends horizontally over the platform 16 and a clamp 90 frictionally engages and is slidably adjustable on this horizontal arm, as is best shown in Figure 1.

The clamp 90 carries a skull cap 92 which is receivable on the head of the patient, being retained in position thereon by means of a strap assembly 94, and the skull cap 92 is also equipped with a downwardly extending face mask 96 30 formed with a pair of eye openings or apertures 98. Needless to say, by loosening the screws 88, the extension 84 may be adjusted vertically as to height, so that the skull cap 92 is properly seated on the head of the patient and the mask 96 covers the patient's face, leaving only the patient's mouth and chin exposed.

The patient, indicated at 100, is seated upon a suitable stool or chair 102 positioned on the platform 16, with his hands gripping the bar 46, and it is to be noted that the invention also includes vibration restraining straps 104, provided with suitable metallic loops 106, so that they may be firmly secured to the arms of the patient. The straps 104 constitute continuations of a connecting strap 108 which passes around the standard 82 and is secured thereto by a suitable screw 110. A reinforcing bracket 112, configurated as is best shown in Figure 4, may be secured to the standard 82, as at 114, and to the strap 108, as at 116, so as to prevent the possibility of the strap 108 sustaining damage by engagement with the standard.

When the invention is placed in use, the patient 100 is seated upon a stool 102 positioned on the platform 16, as has already been described, and the skull cap 92 is placed and secured upon the head of the patient with the mask 96 covering the patient's face, as will be clearly apparent. Moreover, the restraining straps 104 are secured to the patient's arms, substantially as shown.

Thereupon, the motor 56 may be energized, so as to produce reciprocal vibration of the platform 16 and of the hand bar 46, thus violently vibrating or shaking the entire body, including the hands of the patient, while the patient's arms and head remain relatively stationary by virtue of the restraining straps 104, 94, respectively.

Some suitable medicinal preparation should be administered to the patient while the treatment is being given, to which end the holder 80 is provided, so as to receive the cup or glass in which the medicinal preparation is served.

The effect of vibration while certain portions of the patient's body are being held stationary is intended to produce mild muscular or neurotic reflexes or shocks so as to counteract spasmodic contraction of the diaphragm, to which the cause of hiccoughs is attributed. Needless to say, the treatment may be repeated at periodic intervals, if necessary.

It is believed that the advantages and use of the invention will be clearly apparent from the foregoing disclosure, and accordingly further description thereof at this point is deemed unnecessary.

Having described the invention, what is claimed 15 as new is:

1. Hiccough treating apparatus comprising, in combination, a stationary base, a vibratile platform mounted on said base, a vibratile hand bar mounted on said base above said platform, means 20 for reciprocatively vibrating said platform and said hand bar, and vibration restraining arm straps provided above said platform adjacent said bar.

2. Hiccough treating apparatus comprising, in combination, a base including an upright support, a vibratile platform mounted on said base, a vibratile hand bar carried by said support and operatively connected to said platform, and means for reciprocatively vibrating said platform and said bar in relatively opposite directions.

3. The device as defined in claim 2 wherein said base includes an upright standard, together with a free mask suspended from said standard, and a pair of vibration restraining straps provided on said standard, said straps being attachable to the arms of a patient under treatment.

4. Hiccough treating apparatus comprising, in combination, a base including an upright support and an upright standard, a reciprocatively vibratile seat supporting platform mounted on said platform, a lever having upper and lower end portions and fulcrumed intermediately of its length to said support, a hand bar provided at the upper end of said lever, the lower end of said lever being in operative engagement with said platform, a face mask suspended from said standard, a pair of vibration restraining arm straps provided on said standard, and means on said base for reciprocating said platform.

5. The device as defined in claim 4 wherein said means includes a crankshaft, an electric motor coupled to said crankshaft, and a pitman arm operatively connecting said crankshaft to said platform.

6. The device as defined in claim 4 together with means for adjusting the height of said standard.

THOMAS D. ASSMAR.
